UNITED STATES PATENT OFFICE.

DERMOT DONELAN, OF LONDON, ENGLAND.

REMEMBRANCER.

1,378,769.

Specification of Letters Patent. Patented May 17, 1921.

Application filed July 27, 1920. Serial No. 399,304.

To all whom it may concern:

Be it known that I, DERMOT DONELAN, a subject of the King of Great Britain and Ireland, residing at London, England, have 5 invented certain new and useful Improvements in Remembrancers, of which the following is a specification.

This invention relates to improvements in remembrancers, or devices for protection 10 against loss of fountain pens, pencils, or other articles usually carried on the person, and refers more particularly to improvements in devices for this purpose, of the kind wherein a signal is given when the 15 owner moves from the position in which the article has been used, without replacing the article after use.

The device according to the present invention comprises a bell, or its equivalent, 20 and a suitable striker carried by the bell, the device being adapted when the article is in position on the person, for example in the pocket, to rest on such article in such manner that the striker is inoperative, but 25 when the article is removed for use, said device is adapted to depend from the person by a thread, cord, or the like by which it is attached to the person, so that the striker is rendered operative to strike the bell or 30 the like on movement of the person, should the device not be replaced after use.

In the drawings,

Figure 1 is a sectional elevation of one 35 form of the invention adapted to be placed on the upper end or cap of a fountain pen.

Fig. 2 being an elevation showing the device in position on the cap of a fountain pen.

Fig. 3 is a sectional elevation of another 40 form adapted to be placed on the lower end of a pen.

Fig. 4 showing this form in position on a pen.

Fig. 5 is a sectional elevation of a third 45 form adapted to act as a cap for a pen container the device being shown in position on the container which has a pen inside it.

Fig. 6 is a side elevation of a further form applied to a spectacle case.

50 Fig. 7 is a sectional view of the same.

In carrying out the invention according to one form for example in its application to the protection against loss, of a fountain pen, a gong or bell 1, of substantially tubular form, open at one end, is provided with a striker 2 consisting of a ball or bead of

metal secured to one end of a short flexible member such as for example a thread 3, the other end of which is connected to the bell, for instance by knots 4, 5, so that the striker 60 in the free position depends from the top of the bell or the like, so as to be capable of striking the bell or the like. The bell, is provided with a comparatively long securing thread 6 which may be a continuation 65 of the thread 3, by which the device is adapted to be secured to the dress of the person for example by a suitable clip 7 of known form.

When the fountain pen is not required for 70 use, and is in the carrying position on the person, the bell 1 is placed over the closing cap 8 of the pen 9. The bell 1 may be slipped over the cover or cap 8 of the pen 9 and have a clip 10 to replace the pocket 75 clip commonly used to hold a pen in the pocket. When the pen 9 is required for use, the bell 1 is removed from the cap 8, and permitted to depend from the person by its supporting string or cord 6, the pen 80 9 being then removed from its carrying position, and used as required. Should the person inadvertently omit to replace the pen in its carrying position after use, the striker 2 on movement of the person away 85 from the position in which the pen has been used, will strike the bell 1 or the like continuously as the movement is continued, thus drawing the attention of the person to the omission.

In order to render the bell resilient it is provided with slits 10', I have found by experiment that these also improve the resonance of the bell. The bell 1 may be applied to the lower end of a pen as indicated in 95 Fig. 4. In order to permit of a bell 1 of comparatively larger diameter than the pen 9 being used in this way the bell is provided with slight projections 11.

It is to be understood that the invention, 100 although described above in its application to the protection against loss of a fountain pen, is in no way limited to such application, this being merely by way of example, for it will be readily appreciated that the device may 105 be used in connection with the many other articles usually carried on the person, for example, spectacles or pince-nez, pocket knives, pencils, and the like. Such an application is illustrated in Figs. 6 and 7 where 110 the spectacle case 12 is provided with two semi-cylindrical members 13 one being car-

ried by the case 12 and the other by the lid 14. When the case is closed the two members 13 come together and are locked together by the bell 1 being placed over them 5 so that the person carrying the case cannot open it without removing the bell. Should he forget his case and move the bell 1 which is suspended from his person by the thread 6, will ring and remind him of his 10 omission.

I claim:

1. A remembrancer comprising in combination a bell having a striker freely suspended within said bell and flexible means for 15 suspending said bell from the person, and means, on the article of which the person is to be reminded, adapted to receive said bell and to hold said striker in-active, substantially as and for the purpose hereinbefore set forth.

2. A remembrancer for a fountain pen comprising a bell adapted to fit on said pen, said bell having a striker suspended by a flexible member within said bell, and a flexible member attached to said bell for suspending same from the person, substantially as and for the purpose hereinbefore set forth.

3. The combination with an article of an 20 alarm member including a cap to be removably secured to the article, the coöperation of the cap and article holding the alarm member inoperative, and means whereby the 25 alarm member may be connected to the person.

4. A remembrancer comprising a cap adapted to be removably secured to an article, a movable member within the cap and 30 adapted to form an alarm in connection

with the cap, said member being held inoperative for alarm purposes when the cap is on the article, and means for connecting the cap to the person.

5. The combination of an article of a cap-like element arranged for removable connection to the article, a sounding element within the cap and adapted to be held inoperative when the cap is on the article, and a connection to attach said cap to the person.

6. A combination with an article of a 50 remembrancer comprising a bell having a striker suspended within it, the bell being adapted for removable connection with the article to hold the striker inoperative, and means for suspending the bell from the person.

7. The combination with an article of a remembrancer comprising an alarm comprising a bell in the form of a cap for the article, and a striker suspended within the 60 cap, the striker being held inoperative with respect to the bell when the latter is in position on the article, and a flexible connecting means extending from the bell.

8. The combination with an article, of a 65 remembrancer comprising an alarm including a bell in the form of a cap for the article, said bell being longitudinally slotted to render it resilient for coöperation with the article and improve its resonance, a 70 striker suspended within the cap, the striker being held inoperative with respect to the bell when the latter is in position on the article, and a flexible connector extending from the bell.

In testimony whereof I have signed my name to this specification.

DERMOT DONELAN.
